UNITED STATES PATENT OFFICE

108,549

DESIGN FOR A SMOKING STAND

John K. Milton, Chicago, Ill.

Application December 14, 1937, Serial No. 73,617

Term of patent 14 years

To all whom it may concern:

Be it known that I, John K. Milton, a citizen of the United States, residing at Chicago, in the county of Cook and State of Illinois, have invented a new, original, and ornamental Design for a Smoking Stand, of which the following is a specification, reference being had to the accompanying drawing, forming part thereof, in which—

Fig. 1 is a front elevation of the article showing my new design;

Fig. 2 is a side elevation;

Fig. 3 is a top plan view;

Fig. 4 is an enlarged section on the line 4—4 of Fig. 3;

Fig. 5 is a plan section on the line 5—5 of Fig. 1; and

Fig. 6 is a bottom view of a portion of the stand top on an enlarged scale.

I claim:—

The ornamental design for a smoking stand, as shown.

JOHN K. MILTON.
